UNITED STATES PATENT OFFICE.

FREDERICK WILLIAMS, OF ALEXANDRA, NEW ZEALAND.

AUTOMATIC WOOL-WASHING MACHINE.

SPECIFICATION forming part of Letters Patent No. 380,470, dated April 3, 1888.

Application filed July 25, 1887. Serial No. 245,229. (No model.) Patented in New Zealand June 15, 1885, No. 1,462.

To all whom it may concern:

Be it known that I, FREDERICK WILLIAMS, a subject of the Queen of Great Britain, residing at Alexandra, in the county of Vincent,

5 Colony of New Zealand, have invented a new and useful Improvement in Automatic Wool-Washers, (for which I have obtained a patent in New Zealand, No. 1,462, bearing date June 15, 1885,) of which the following is a specification.

10 My invention consists of a novel washer, which is automatic and effective in operation, of simple and inexpensive construction, and possesses other advantages, as will be herein- 15 after fully set forth and claimed.

Figure 1 represents a perspective view of a wool-washing machine embodying my invention. Fig. 2 represents a top or plan view thereof, partly broken away. Fig. 3 represents 20 a vertical section of the water-inlet and gate in line *x x*, Fig. 1. Fig. 4 represents a horizontal section of a portion of the bottom of the washing-vessel and covering-plate, with catches and flanges for holding the same in 25 place in line *y y*, Fig. 2. Fig. 5 represents a perspective view of the bar which supports the water-inlet chute, the central portion being broken away. Fig. 6 represents a perspective view of the center block, showing 30 the perforations therein. Fig. 7 represents a perspective inner view of one end of the washing-vessel, the inlet-chute being removed.

Similar letters of reference indicate corresponding parts in the several figures.

35 Referring to the drawings, A represents a circular frame, preferably oval in form, which supports the washing chamber or vessel B, consisting of a bottom, *a*, and side *b*, constructed of zinc or other suitable metal or material, said 40 bottom and side being perforated in part or entirely so, if desired. Rising from the bottom *a* is a center or block, C, which is of oval or other form, with perforations in its side, and constructed of zinc or other suitable metal or 45 material.

D represents a water-inlet consisting of a chute or tube, which is secured to the side *b* of the chamber and center C, so as to occupy a position over the space formed by said side 50 and center. The inner end of the chute is open and occupied by a gate, E, which may be raised

and lowered by screws F, so as to be vertically adjusted relatively to the quantity or pressure of water it is desired to inject or admit into the washing-chamber.

55

In order to sustain the gate and prevent displacement thereof, there is secured to the side of the chute a bar, F', which bears against the front of said gate and braces the same,

60 In order to sustain the inlet D and prevent vertical displacement thereof, there is secured to the side *b* of the washing-chamber and center C a bar, G, which assists to support the inlet and brace the under side thereof.

The perforations K of the bottom and side 65 of the washing-chamber are arranged in sections or groups, and there are provided for the groups covering-plates H J. The plate H acts as a false bottom for the bottom *a* of the chamber, and is held in place by a flange, *c*, 70 on said bottom *a* and catches *d*, which are pivoted to said bottom *a* and engage with the plate H. (See Figs. 2 and 4.) The plates J cover the side perforations of the chamber, and are held in place by flanges *e* on said side. 75 (See Figs. 1 and 7.) In the side *b* of the chamber is a group of perforations, K', which are about the water-line of said chamber, the center or block C also being partly perforated.

The operation is as follows: The device as 80 constructed is placed in a dam, river, box, or other convenient place, whereby it will be in water to nearly its top and supplied with water at the required level, the wool to be washed being placed in the chamber B. Water is 85 forcibly directed into the chute D and escapes therefrom at the space below the gate E, and is ejected downward in almost perpendicular direction, and thus injected forcibly into the water in the vessel B, the bottom lips and corners of said gate or the adjacent parts of the chute being beveled, so that the water spreads in width. The action of the injected water creates a current in the vessel B, causing the water to flow around the center C, whereby 90 the wool is carried around said vessel, returning under the chute D, and being agitated and subjected to the action of the circulating water, so that the dirt is beaten out and the wool effectively and uniformly washed of its impurities, it being noticed that the inflowing water from the chute is the automatic agent for 95 100

creating the current within the chamber B. The dirty water escapes through the lower side perforations, K, and the scum discharges through the perforations K'. When the water 5 in the chamber is as clean as the supply, the washing of the wool is complete, and the same may be removed.

The speed of the current of water in the vessel is to some extent controlled or regulated 10 by the slides or plates H and J, the water flowing more rapidly from the vessel when the plates are removed, and as a matter of course less rapidly when the plates are in position for closing the perforations.

15 For washing "locks" or other wools which may contain "second cuts" or "chips," a greater number of perforations should be uncovered or exposed, so that there will be less suction through each single opening, whereby 20 choking of the openings is prevented and necessity of frequently cleaning the same obviated. During the washing operation the wool is kept within view of the workman, so that the work may be inspected as it progresses.

25 Among other advantages of the present invention, there is great saving in the cost of washing, the wool is being evenly washed, it being left free, so that "no breaking out" is required before spreading, and, being thoroughly opened, it quickly dries. There are no 30 movable parts to get out of order, the fiber or staple of the wool is not injured, and roping or entanglement is prevented.

The frame is constructed of uprights f, circumferential rims g, radial beams h, and a cen- 35

tral bracing, j, all firmly secured together, forming a strong structure.

Having thus described my invention, what I claim as new, and desire to secure by Letters Patent, is—

1. In a wool-washing machine, a washing-chamber having perforated walls and plates for covering the same, substantially as described.

2. A wool-washing machine having a wash- 45 ing-vessel with a center block and an inlet-chute secured to said center block and the side of the vessel, substantially as described.

3. A wool-washing machine having a wash- 50 ing-vessel with perforations K in the bottom and sides, covering-plates for said perforations, a center block, a water-inlet chute secured to said block and the side of the vessel, and provided with a vertically-adjustable gate, said parts being combined substantially as and for 55 the purpose set forth.

4. A wool-washing machine having a wash- 60 ing-vessel with perforations K in the sides thereof, and perforations K' in the side about the water-level of said vessel, a center block, and a water-inlet chute secured to said block and to the side of the vessel, said parts being combined substantially as described.

In witness whereof I have signed my name.
FREDERICK WILLIAMS.

In presence of—

J. F. HARPER,
Accountant Bank of New Zealand, Dunedin.

C. H. HOWARD,
Solicitor, Dunedin, N. Z.
